AMPLIFIER APPARATUS

Wesley W. Dewey, Chanute, Kans., assignor to Kustom
Electronics, Inc., Chanute, Kans.

Filed July 17, 1972, Ser. No. 272,313

Term of patent 14 years

Int. Cl. D14—03

U.S. Cl. D26—14 L

Fig. 2.

Fig. 3.

Fig. 4.

Fig. 5.

Fig. 6.

FIG. 1 is a perspective view of an amplifier or similar electronic apparatus embodying the new design;

FIG. 2 is a front elevational view thereof;

FIG. 3 is a top plan view thereof;

FIG. 4 is a rear elevation thereof;

FIG. 5 is a view taken from the right hand end of the amplifier shown in FIG. 2; and

FIG. 6 is a side elevational view taken from the left hand elevational view shown in FIG. 2.

I claim:

The ornamental design for an amplifier apparatus, as shown.
